UNITED STATES PATENT OFFICE.

JOHN ZANDER, OF CHICAGO, ILLINOIS, ASSIGNOR TO UNION CARBIDE COMPANY, OF CHICAGO, ILLINOIS, A CORPORATION OF VIRGINIA.

CAN-OPENER.

No. 886,913.

Specification of Letters Patent.

Patented May 5, 1908.

Application filed January 28, 1908. Serial No. 413,019.

To all whom it may concern:

Be it known that I, JOHN ZANDER, a citizen of the United States, residing at Chicago, in the county of Cook and State of Illinois, 5 have invented certain new and useful Improvements in Can-Openers, of which the following is a specification.

This invention is a tool for opening cans, especially the metal cans which are used for 10 storing and shipping calcium carbide and the closure of which comprises an apertured fixed head, receiving a screw-cover, and an imperforate outer slip cover.

The tool consists of a bar having a lateral 15 end fulcrumed to rest on the edge of the outer slip-cover, and a blade adjacent to the fulcrum but lying in a plane substantially at right angles thereto, to enter beneath the flange of the slip-cover and raise and detach 20 this cover from the fixed head, when the tool is pulled upward by the handle at its outer end. The tool also has a lug, extending from the bar on the side opposite the cover-detaching blade, which lug coöperates with 25 the fulcrum in removing or replacing the screw-cover which closes the opening in the fixed head.

Referring to the accompanying drawings, Figure 1 is a perspective view of the tool; 30 Fig. 2 is a sectional view of the upper end of a carbid-can, having an inner fixed head and screw cover and an outer slip-cover; Fig. 3 is a perspective view of the upper end of this carbid-can, with the slip-cover in place, 35 showing the tool in position to remove this cover; and Fig. 4 is a plan view of the upper end of the carbid-can, with the slip-cover removed, showing the tool in position to unscrew the screw-cover.

The can-opener, shown in Fig. 1, consists 40 of a rigid bar 1, preferably a flat strip of tempered steel, the end 2 of which is forged round and bent laterally to provide a terminal fulcrum 3. Adjacent to the round end 2 is the cover-detaching blade 4, made by forging the offset end of the bar 1 to a sharp edge. From the side of the bar opposite to the blade 4, extends a lug 5 having a squared end 6, which coöperates with the 50 fulcrum 3 in removing or replacing the

screw-cover. The outer end of the bar may be provided with a wooden handle 7.

The carbid-can, for the opening of which this tool is specially designed, is shown in Figs. 2, 3 and 4. This can comprises a body 55 8 having an inner fixed head 9 and an outer slip-cover 10. The fixed head has a central marginally-threaded opening 11 which is closed by a screw-cover 12. This cover has a diametral piece 13 which serves as a handle 60 in screwing the cover out or in. The slip-cover 10 has a marginal flange 14 which is slightly crimped beneath the edge of the fixed head 9. In employing the tool to open this can, the fulcrum 3 is placed on the upper 65 edge of the slip-cover 10, as shown in Fig. 3, and the blade 4 is inserted beneath the flange of this cover. By raising the handle 7 of the tool, the flange is detached from the top of the can at one point. By shifting the fulcrum 3 to several points, the cover may be easily and quickly removed. The tool may then be used to unscrew the cover 12, by applying it to the cover in the position shown by full lines in Fig. 4, with 75 the fulcrum 3 resting against one end of the cover-handle 13 and the lug 5 resting against the vertical threaded edge of the cover. The tool is then rotated in a contraclock-wise direction. To replace the screw-cover the 80 tool is applied in the position shown by dotted lines in Fig. 4, the fulcrum 3 then bearing against the opposite side of the cover-handle 13 and being rotated in a clock-wise direction.

I claim:

1. A can-opener, consisting of a bar having a lateral end fulcrum and an intermediate cover-detaching blade, said fulcrum and blade situate in different planes.

2. A can-opener, consisting of a bar having a lateral end fulcrum, a cover-detaching blade adjacent to said fulcrum, and a lug remote from said fulcrum, said blade and lug being oppositely disposed.

In testimony whereof, I affix my signature 95 in presence of two witnesses.

JOHN ZANDER.
